CLAIM

The ornamental design for an end cover of a tool holder, as shown and described.

DESCRIPTION

FIG. 1 is an upper perspective view of an end cover of a tool holder showing my new design.

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom perspective view thereof; and,

FIG. 9 is an upper perspective view showing two of an end cover of a tool holder of my new design affixed to a tool holder with tools secured therein.

The broken lines in the drawings illustrate environmental subject matter and form no part of the claimed design.
